OIL AND ENGINE COOLING SYSTEM

Eric O. Schjolin, Pontiac, Mich., assignor to
 Yellow Truck & Coach Manufacturing Company, Pontiac, Mich., a corporation of Maine

Application October 26, 1929, Serial No. 402,694

17 Claims. (Cl. 123—196)

This invention relates to the cooling of lubricant oils used upon water-cooled engines; and it contemplates not only the use of special water circuits but the use of special oil circuits,—one 5 preferred embodiment including an oil cooler and an oil pump in a delivery line from an oil tank to an engine, an oil pump in a return line from the engine sump to said tank, and thermostatic means for operating a valve controlling a by-pass between cooling-water circuits, and thereby 10 varying the flow and the temperature of water advanced to said cooler.

As in the case of the prior invention of Ramsaur, as described and claimed in application 15 Serial No. 354,245, filed April 11, 1929, it is an object of this invention to provide internal combustion engines with distinct but conditionally intercommunicating circuits for a heat exchange liquid such as water,—one of said circuits being 20 employed, in a known manner, to cool an engine block and associated parts and the other of said circuits being employed exclusively in cooling lubricating oil; and, in preferred embodiments, this invention contemplates not only the use of 25 the mentioned plurality of oil pumps (optionally driven from one shaft or otherwise consolidated into a single unit) and the use of a plurality of separate or consolidated water pumps, but the use of an over-flow by-pass or by-passes, one of these 30 being preferably provided between separate radiators or radiator sections; and the use also of a valve-controlled by-pass, which is subject to regulation by said thermostatic means, for a proportioning effect in the admission of water to 35 and/or the exit of water from one or both of said pumps.

It is a further object of this invention to provide a special pump organization with which four conduits communicate, a single set of vanes and 40 a mentioned valve being effective to vary the flow of cooling water, or the like, therethrough; and it is also an object of this invention to provide a radiator assembly specialized with reference to the use of a main radiator section and an 45 auxiliary radiator section for cooling normally separate streams of water, or the like,—a front set of tubes being preferably included in the auxiliary radiator and its water being circulated through a heat exchange unit normally used in 50 cooling the lubricating oil. Said radiator assembly may include means permitting a conditional overflow from one of said sections into the other; and cross flow tubes are preferably included in the auxiliary radiator or section.

55 Other objects of this invention, including

means whereby circulation through the auxiliary radiator or section may be automatically deferred during a warming-up period, and including also various features adapting a single oil tank to be used (upon busses, trucks, or the like) in connection with a plurality of engines, each associated with a side radiator or radiator sections, and including also various preferred subcombinations or details of construction and relationship, may be best appreciated from the following description of an illustrative embodiment of the invention, taken in connection with the appended claims and the accompanying drawings.

Figure 1 is a highly conventionalized diagram indicating the separate circulations of (1) oil-tempering water, in an outer circuit, (2) engine-cooling water in an inner circuit (stippled) and (3) oil (via small pipes)—a by-pass valve, between the first and second circuits, being shown as thermostatically closed, as in normal running.

Figure 2 is a diagram similar to Figure 1, but showing the mentioned valve as shifted to an initial oil-warming position, whereby engine-cooling water is diverted into the oil-tempering water circuit, the mentioned by-pass being opened. Stippling is herein applied additionally to the only portion of the oil-tempering water circuit which is functional under the conditions referred to; and optional features of modification are suggested.

Figure 3 is a top plan view, with parts broken away, showing one of a pair of side-facing sectional radiators and associated parts appropriate to a twin-engine installation in an automotive vehicle.

Figure 4 is, for the most part, a vertical sectional view, on a slightly larger scale, through a water pump organization having four conduit connections,—said pump being provided with a thermostatically or otherwise remotely controllable valve. This view may be regarded as taken substantially as indicated by the broken line 4—4 of Figure 3.

Figure 5 shows the organization shown in Figure 4 from substantially the viewpoint indicated by the arrow 5 of Figure 4,—parts being shown in plan and other parts being broken away to levels indicated by lines 5'—5' of Figures 4 and 6.

Figure 6 is a partial vertical sectional view taken substantially as indicated by the broken lines 6—6 of Figures 3 and 5.

Figure 7 is a fragmentary section through the organization shown in Figures 4, 5, and 6 taken substantially as indicated by line 7—7 of Figure 8, but with a by-pass valve positioned differently than in Figure 4.

Figure 8 is a fragmentary view of the organization shown in Figures 4, 5, 6, and 7, partly in plan, partly as suggested by the lines 8—8 of Figures 6 and 7 and partly in section on the line 8—8' of Figure 4.

Figure 9 is a vertical sectional detail view, taken substantially as indicated by the broken line 9—9 of Figure 8.

Figure 10 is a detail vertical sectional view, taken substantially as indicated by the line 10—10' of Figure 8.

Referring first to diagrammatic Figure 1, a cooling circuit for engine 11 is shown as comprising, in addition to a main radiator or radiator section 12, a hot water pipe or radiator feed conduit 13 and also a return conduit in the form of pipes 14, 15, 15',—a pump or pump section 16 being shown as interposed between pipes 14 and 15. A normally separate oil-cooling circuit is shown as including, in addition to an oil cooler or tempering unit 17 and an auxiliary radiator or radiator section 18, a separate radiator feed pipe 19 and a return pipe including sections 20 and 21, between which is interposed a pump or pump section 16'. The normal separateness of the mentioned circuits may depend upon the position of a valve element 22, or its equivalent,—the shifting of this element from a position such as that illustrated in full lines in Figure 1 to a position such as that therein shown in dotted lines being effective both to discontinue circulation through pipe 20 and to open communication of a by-pass between pipes 15 and 21, to vary the temperature of the heat-transfer liquid fed to unit 17. The manipulation of valve 22 may be effected by remote and/or automatic means such as a thermostat 23, shown as connected with a lever arm on the shaft of valve 22 by means of a rod 25,—a low temperature within the thermostat 23 being effective to hold open the by-pass 26, and thereby to admit a suitable proportion of the somewhat warmer engine-cooling water into the oil-tempering water circuit.

A lubricating oil circuit which includes the engine 11 and the oil cooler or tempering unit 17 may comprise both a pipe or conduit 27, leading from said "cooler", or from the thermostat 23, to the engine 11, and a pipe or conduit 28 leading from the sump or oil pan (not shown) of said engine through a pump 29 to a main oil tank or reservoir 30,—means such as an additional (pressure-feed) oil pump 31, connected with the tank 30 and the cooler 17 by pipes 32 and 33 being preferably also included in said oil circuit in case the tank 30 is not a pressure tank.

As hereinafter more fully indicated, the water pump sections 16, 16' may be combined into a single unit driven by or from means such as a fan shaft 34 or a shaft 34', coupled therewith; and the oil pumps 29 and 31 may be indirectly driven from the same shaft, as by means of a gear 35 on said shaft and a cooperating gear 36 on a drive shaft 37, shown as common to the last-mentioned pumps. Water replenishment may be effected by common means such as one or more elevated water tanks 38, shown as communicating by a pipe or pipes 39 with the main radiator feed conduit or conduits 13.

My invention may be applied to two engine installations such as are found on some automotive vehicles by equipping both engines with engine cooling and lubricating systems and lubricant cooling systems of the type shown in Figure 1 and heretofore described. This is indicated in Figure 1 by the showing of the parts 17', 28', 29', 31', 33'

and 40'. These parts are similar to the parts bearing the same reference characters unprimed and are to be understood as constituting elements of the lubricating system of an engine (not shown) similar to that designated by the reference character 11. The engine and lubricant cooling systems of the two engines are preferably entirely independent of each other, but as Figure 1 shows the lubricating systems of the two engines preferably communicate with a single 10 reservoir 30.

When "dry-sump" operation is intended, the scavenging pumps 29 (and 29') of the system (or the respective twin systems) may be larger than the pressure pump 31 (or the respective pressure-feed pumps 31, 31') delivering into the cooler 17 (and 17'); and the capacity of the water pump or pump section 16 may exceed that of pump or pump section 16' in proportion as the maximum volume of water to be handled in the engine-cooling circuit exceeds that to be handled in the oil cooling circuit.

Whether or not filtration means are included within either or both of the mentioned water circuits, strainers such as are diagrammatically suggested at 40, 40', may advantageously be provided either in connection with the inlets or the outlets of the main oil tank 30, or its equivalent; and, in order to provide not only for unequal thermal expansion of the water in the respective cooling circuits described but to permit an advance of oil cooling or warming water through the pipes 21 and 19 even when the valve 22 occupies that dotted-line position which precludes circulation through pipe 20, additional and conditional communication is preferably provided between the described cooling circuits,—as by a by-pass in the form of a "spillway" or overflow connection at 41 between the mentioned radiators or radiator sections; and one advantageous type of radiator organization including features suitable for the purpose last referred to will next be described.

Referring to Figure 3, longitudinal chassis or frame elements such as are indicated at 42 and 42' may directly or indirectly support not only the mentioned engines 11 but also radiator organizations each including both an inwardly disposed main radiator section 12 and a forwardly or outwardly disposed auxiliary radiator section 18,—these being shown as including a common outer wall or frame element 43. The main radiator section is shown as including, in addition to cross-flow tubes 44, upright headers 45 and 45' (with which the pipes 13 and 14 respectively communicate) and the auxiliary radiator section may comprise cross-flow tubes 46,—terminating within an upright intake header 47 (with which the pipe 19 of the oil cooling water circuit is connected) and within an outlet header 47' (with which the out-flow pipe 20, leading toward the cooler 17 but conditionally closed by valve 22, is connected). A valveless but conditionally effective overflow or by-pass connection may be provided, as at 41, by suitably aperturing or eliminating an upper part of a partition wall, common to intake headers 45 and 47. Partition wall 41' need not be correspondingly apertured.

Referring further to Figure 3, bearing arms 49 and 50 are suggested for the support of the extension 34' of the shaft of the fan 34'' from a 70 mentioned frame element 42'; the mentioned water pumps or pump sections are combined into a single unit 16—16', with which both the engine-cooling water pipes 14 and 15 and also the oil-cooling water pipes 20 and 19 are connected; 75

cooler 17 may be combined with the pump unit; and the thermostat unit 23 is shown so supported, opposite the cooler 17, as to permit a relatively direct flow of cooled oil therebetween, 5 through a short pipe or conduit 51, for delivery into pipe 21, and thereby to the engine 11.

As best shown in Figures 4, 5 and 7-10, the pumps 16 and 16' may advantageously include a casing or body comprising a main shell or section 53, a terminal or thrust-bearing section 54 and a valve-containing base section 55. The sections 53 and 54 may be provided with bearings for the shaft 34' and with connections at 57 and 58 suitable for engine-cooling water intake pipe 14 and the corresponding delivery pipe 15; and the valve-containing section 55 may be provided with threaded and/or flanged intake opening member 58 suitable for connection with the auxiliary radiator pipe 20, and with a downwardly inclined 20 or other delivery conduit or passage 59—which may lead to the cooling-water spaces of the oil "cooler" or tempering unit 17.

The main pump shell or section 53 is shown as provided with two concentric and substantially 25 cylindrical chambers 60 and 61, sufficiently separated by an inwardly-extending bead or partitioning element 62; and oppositely projecting sets of vanes 63 and 64, comprising the rotors respectively of pump sections 16 and 16', are 30 shown as carried by a single disk or radial web 65. In order at times to handle the water of both circuits, vanes 64 may be the larger; and the web 65 may be formed integral with a hub 66, keyed or otherwise secured to the shaft 34', or its 35 equivalent,—optional details of preferred construction being indicated in the drawing. It will be understood that when this pump is connected as described, engine-cooling water entering through the pipe 14 into the pump chamber 61 40 will, when the valve 22 occupies the position shown in full lines in Figure 1 and in dotted lines in Figures 4 and 7, be discharged therefrom through the outlet 56 and the pipes 15 and 15' and will, when said valve occupies the position in 45 which it is shown in broken lines in Figure 1 and in solid lines in Figures 7, 8, and 9, be discharged from the chamber 61 in part through the outlet 56 and the pipes 15 and 15' and in part downwardly, through a passage 67, into an intermediate chamber 68, in which the valve 22 is located,—rising thence through an upwardly-extending by-pass passage 66, and into the chamber 60 of the auxiliary pump section comprising 50 vanes 63. The depression of valve 22 to the position last referred to serves also to close the intake passage through flanged member 58, communicating with the auxiliary radiator section pipe 20,—thereby preventing advance of water through said section into pump chamber 60; and 55 an intermediate positioning of the valve 22 accordingly implies a proportioning of the relatively cool oil-cooling circuit water, as admitted through pipe 20, and the relatively warm water of the engine-cooling water circuit, as admitted 60 through pipe 14,—the cool water or warm water or any appropriate mixture thereof being, in any case, impelled by pump or pump section 16' (vanes 63) through the passage 59 into the heat exchange unit 17, or its equivalent.

70 In preference to positioning the thermostat 23, or alternative means for remote control of the valve 22, within the engine 11 or within the cooler 17 or elsewhere, said thermostat may include a main body element 70, suitable for attachment to the cooler 17 and containing a bel-

lows 71, of any suitable type. A movable end plate 72 of the illustrated bellows is shown as connected with an operating arm 73, upon shaft 74 carrying the valve 22, by means of rod 25; the thermostat body element 70 may cooperate 5 with a cylindrical shell 76, having a flange 77, in the provision of an oil chamber 78, surrounding the bellows 71; the bellows may contain a sealed-in fluid, to produce expansion as warmed; cylindrical shell 76 may support said bellows by 10 means of a central boss 78'; and said shell may be retained by means such as a thermostat closure element 79 engaging the flange 77 and directly or indirectly providing a stop for a spring 80, if employed. Said spring is shown as so interposed between the end plate 72 of bellows 71 and a washer 81 as incidentally to retain and compress a packing element or composition 82,—serving to exclude dust from a chamber 83, directly containing the bellows 71. As best 20 shown in Figures 4 and 8, a plate 84 may serve not only as a closure element for the passage 68 in which the valve 22 is movable, but to provide bearing bosses 85 and 86 for the shaft 74 25 of said valve; and, in order to obviate leakage along said shaft, means such as a usual or special gland may be provided. For the purpose last referred to, the boss 85 is shown as provided with a chamber 87 adapted to retain packing 30 88 under a compression due to a compression spring 89. This spring is shown as surrounding the outer boss 86 and as interposed between a fixed stop 90 and a movable stop in the form of a washer 91,—the shaft 74 being 35 provided with a cylindrical element 92, snugly rotatable within the cylindrical chamber 87.

Although the cooler 17 might have any preferred alternative construction, said cooler is shown in Figures 6, 7, and 8 as comprising a main body element 93. This is optionally integral with pump casting 55 and it may be provided as at 94, with an opening for an oil inlet fitting 95 (with which the oil feed pipe 33 may be connected) and with a similar opening 96 for an outlet fitting 97,—with which the short pipe 51, leading to the thermostat 23, may be connected. Said cooler may also include a removable plate 98, shown as retained by means of bolts 99 and nuts 100, closing a bottom opening through which not only the fittings 95 and 97 but any suitable heat exchange elements may be introduced. For example, a sheet metal shell 101 may be surrounded, near the respective ends thereof, with rubber or similar gaskets 102 and 103, serving not only to support the said shell but to define an inlet header space at 104 and an outlet header space at 105 in such manner that "cooling" water is forced to pass transversely through spaces 106, provided between the convolutions of flat or other oil-containing conduits 107, terminally communicating with the mentioned fittings 95 and 97: but the exact configuration of the heat-exchange conduits 107 is immaterial to this invention.

As has been incidentally indicated, the temperature of the cooling (or warming) water advanced through the spaces 106, to temper the oil in conduits 107, depends upon the position in which the interior valve 22, or its equivalent, 65 may be held by means such as the described thermostat,—to whose chamber 78 oil may be admitted from pipe 51 by way of an inlet opening 108, to exit into pipe 21 by way of an outlet opening 109; but it will be obvious that, without 70

75

departure from the scope of the present invention, many of the described elements might be replaced by known equivalents; and optional features of modification of the general arrangement 5 of units in this cooling system are suggested in Figure 2.

In the figure last referred to, parts corresponding 10 to those mentioned in connection with Figure 1 being generally identified by the same reference characters but with an "a" added to each character, the engine-cooling water pump 16a is shown as entirely distinct from the oil-cooling water pump 16a', in order to obviate risk of any undue heating effect as a result of the combining of 15 pump sections and/or the positioning of a pump or pump section immediately in advance of the cooler 17a; but, as above indicated, it should be understood not only that various features of the present invention might be independently employed but also that the numerous modifications, 20 additional to those suggested herein, might easily be devised,—all within the scope of the present invention.

I claim:

25 1. In an engine-cooling and lubricating system: a main radiator section in a circuit for an engine-cooling heat-transfer liquid; an auxiliary radiator section in a circuit for a lubricant temperature regulating liquid in which is included a heat 30 transfer unit through which lubricant is adapted to flow in heat exchanging relation to the temperature regulating liquid; means for variably interconnecting and conditionally separating said circuits; means for advancing the liquid in said 35 circuits; and means automatically compensating for unequal expansion and flow in said circuits,—said last-mentioned means including an overflow connection between said radiator sections.

2. In an engine-cooling and lubricating system: 40 a main radiator section in a circuit for an engine-cooling heat-transfer liquid; an auxiliary radiator section in a circuit for a lubricant temperature regulating liquid in which is included a heat 45 transfer unit through which lubricant is adapted to flow in heat exchanging relation to the temperature regulating liquid; means for variably interconnecting and conditionally separating said circuits; means for advancing the liquid in said 50 circuits; a lubricant reservoir and separate means for pumping lubricant thereto and therefrom relatively to said engine.

3. In an engine-cooling and lubricating system: 55 a main radiator section in an engine-cooling circuit for a heat-transfer liquid; an auxiliary radiator section in a circuit for a lubricant temperature regulating liquid in which is included a heat transfer unit through which lubricant is adapted to flow in heat exchanging relation to the temperature regulating liquid; and means for advancing 60 said liquid in said circuits,—said advancing means including pump means interiorly provided with means for conditionally separating and interconnecting said circuits to vary the circulation of said heat-transfer liquid in both of 65 said circuits and the feed to said heat transfer unit.

4. In an engine-cooling and lubricating system: 70 a main radiator section in an engine-cooling circuit for a heat-transfer liquid; an auxiliary radiator section in a circuit for a lubricant temperature regulating liquid in which is included a heat transfer unit through which lubricant is adapted to flow in heat exchanging relation to the temperature regulating liquid; means for advancing 75 said liquid in said circuits; and a thermo-

stat external to said unit,—said advancing means including pump means provided with internal means for conditionally separating and interconnecting said circuits to vary the circulation of said liquid in one of said circuits and the feed to 5 the heat transfer unit in response to variations in the temperature of lubricant to which said thermostat is exposed.

5. In an engine-cooling and lubricating system: 10 a main radiator section in an engine-cooling circuit; an auxiliary radiator section in a circuit for a lubricant temperature regulating liquid in which is included a heat transfer unit through which lubricant is adapted to flow in heat exchanging relation to the temperature regulating 15 liquid; means for advancing a liquid in said circuits; said circuits being provided with overflow means of conditional interconnection between said radiator sections to compensate automatically for unequal expansion and flow in said circuits and with thermostatically operated means for conditionally separating and interconnecting the circuits at another point to vary the feed to 20 the heat transfer unit.

6. For use in a two-circuit cooling system: a 25 radiator organization comprising a main section and an auxiliary section having a conditionally effective interconnection therebetween,—at least one of said sections being of cross-flow type.

7. For use in a two-circuit cooling system: a 30 radiator organization comprising a main section and an auxiliary section having a conditionally effective interconnection therebetween,—said auxiliary section being placed outwardly of said 35 main section.

8. For use in a two-circuit cooling system: a 40 radiator organization comprising a main section and an auxiliary section having a conditionally effective interconnection therebetween,—said organization comprising a common frame and said 45 sections being provided with common means of replenishment.

9. For use in a two-circuit cooling system: a 50 centrifugal pump organization having an inlet for connection to each of the circuits, an outlet 45 for connection to each of the circuits, and internal valve and by-pass means for varying the circulation therethrough.

10. For use in a two-circuit cooling system: a 55 centrifugal pump organization having an inlet for connection to each of the circuits, an outlet for connection to each of the circuits, and internal valve and by-pass means for varying the circulation therethrough,—a heat-exchange unit casting being formed integral with a casing of said 60 pump organization.

11. For use in a two-circuit cooling system: a 65 centrifugal pump organization having an inlet for connection to each of the circuits, an outlet for connection to each of the circuits, and internal valve and by-pass means for varying the circulation therethrough, a heat-exchange unit being 70 directly connected to said pump organization and provided with thermostatic means for moving said valve.

12. In apparatus of the type described, a heat 75 exchanger which includes two sets of heat exchanging elements subject to a common volume of temperature regulating medium so arranged that one set of heat exchanging elements is subjected to the action of the common volume of temperature regulating medium after it has acted on the other set, a fluid circuit of which one set of heat exchanging elements constitutes an element, and another fluid circuit of which the other 80

set of heat exchanging elements constitutes an element.

13. In apparatus of the class described, two circuits for fluids, means in each circuit for circulating a fluid through it, and means interconnecting the first mentioned means so as to effect inter-communication between the two circuits.

14. The invention claimed in claim 13 plus temperature controlled means for regulating the interconnection.

15. In apparatus of the class described, a fluid pump, a plurality of impeller chambers, passages interconnecting the impeller chambers, and temperature controlled means regulating the flow of fluid through the passages.

16. In apparatus of the type described, a heat exchanger which includes two sets of heat exchanging elements subject to a common volume of temperature regulating medium so arranged that one set of heat exchanging elements is sub-

jected to the action of the common volume of temperature regulating medium after it has acted on the other set, a fluid circuit of which one set of heat exchanging elements constitutes an element, another fluid circuit of which the other set of heat exchanging elements constitutes an element, and means of communication between the two sets of heat exchanging elements.

17. In an internal combustion engine, an engine cooling system which includes a liquid cooling radiator, a lubricating system which includes a heat exchanger, a lubricant cooling system which includes a liquid cooling radiator and the mentioned heat exchanger, interconnections between the engine cooling system and the lubricant cooling system, and means by which liquid from the lubricant cooling system may be compelled to pass through the engine cooling system to reach the heat exchanger.

ERIC O. SCHJOLIN. 20
